Patented Sept. 2, 1919.

UNITED STATES PATENT OFFICE.

NICHOLAS JOSEPH MIANO, OF JAMAICA, NEW YORK, ASSIGNOR TO UNIVERSAL FIXTURE CORPORATION, OF NEW YORK, N. Y., A CORPORATION OF NEW YORK.

DISPLAY-FIXTURE.

1,314,887.

Specification of Letters Patent.

Patented Sept. 2, 1919.

Application filed January 24, 1919. Serial No. 272,960.

To all whom it may concern:

Be it known that I, NICHOLAS JOSEPH MIANO, a citizen of the United States, and resident of Jamaica, in the borough and county of Queens, Long Island, State of New York, have invented certain new and useful Improvements in Display-Fixtures, of which the following is a specification.

This invention relates to improvements in display fixtures, and particularly to swinging panels for displaying articles.

One of the objects of the invention is to provide a swinging panel for display racks having means for supporting a plurality of disk records for phonographs, or similar disk-like articles, substantially flatly against the two faces of the panel, in such manner that the articles may be inspected while on the panel and may be readily removed when desired.

Another object of the invention is to provide a display panel for disk records, or the like, having relatively shallow pockets arranged one above the other in such manner that the upper portion of a record supported in one pocket will overlie a portion of the pocket next above, thereby assisting in holding the pockets and records closely against the face of the panel and enabling a maximum number of records to be displayed on a panel.

A further object of the invention is to provide a panel having a series of relatively shallow superposed pockets the mouths and bottoms of which dip from their sides toward the center, whereby said pockets are adapted to securely support disk phonograph records flatly against the face of the panel and the same time leave the upper portion and center of the record exposed, thus permitting the title of the record to be readily seen and enabling the record to be easily grasped and removed from the pocket.

A further highly important object of the invention is the provision of a display panel having a series of superposed horizontal slots therein and a plurality of duplex pockets adapted to support articles on opposite sides of the panel and having the bottom portions thereof connected together through said slots.

Another important object of the invention is the provision of means for supporting articles on opposite sides of a panel,

comprising a pair of horizontal strips secured at their ends to opposite faces of the panel and having their upper and lower edges free from the panel, the lower edges of said strips being connected together intermediate their ends through a transversely extending slot in the panel.

In the drawing, Figure 1 is a side elevation of a panel constructed in accordance with the invention, mounted in a suitable supporting means;

Fig. 2 a vertical sectional view on the line II-II of Fig. 1;

Fig. 3 a detail horizontal sectional view of a portion of the panel;

Fig. 4 a fragmentary side elevation of the panel board removed from the panel frame; and

Fig. 5 a detail view showing a pair of connected record holding strips detached from the panel board.

In the drawings, the invention is shown embodied in a swinging panel display fixture, but it will be obvious that the invention is also applicable for use in connection with fixtures having stationary panels.

Referring to the various parts by numerals, 1 designates a swinging panel support which is mounted on a vertical rod 2 and is formed with the flange 3 at its upper end and a flange 4 at its lower end. The rod 2 is supported by brackets 5 secured to a wall 6 or other rigid support.

The swinging display panel comprises a rigid rectangular frame formed with vertical side rods 7 and 8 connected near their lower ends by a transverse rod 9. The ends of rod 7 are pivotally held to flanges 3 and 4 of the panel support, and rods 7, 8 and 9 support a channel frame 10 having its open side facing inwardly. The upper ends of the side members of the channel frame 10 are open and said side members are connected by a removable channel bar 10'. The rods 7 and 8 are connected adjacent their upper ends by a bar 11.

A panel board 12 of heavy cardboard, or other suitable material, is removably held within the channel frame 10 and said board is provided with a vertical series of superposed transversely extending slots 12a, preferably curved as shown. Two series of strips of fabric 13 and 14 extend transversely across the panel board at opposite sides thereof, each strip 13 being arranged

directly opposite one of the strips 14, and the ends of the strips of both series being stitched to the panel board by vertical rows of stitches 15.

5 Both the upper and lower edges of the strips 13 and 14 are preferably curved as shown and reinforced by suitable binding strips 16. The lower edges of each pair of oppositely disposed strips extend parallel 10 with one of the slots 12^a in the panel board, and for a portion of their length extend through said slots and are stitched together at 17, thus forming a pocket divided vertically longitudinally thereof by the panel 15 board and having its sides connected together centrally of the pocket through a slot in the board, the pocket being open at the bottom at each side of said intermediate connection. It will be obvious that the 20 sides of the pocket and the intermediate connection 17 may be cut in one place if desired.

When designed for holding disk records 25 for phonographs the strips 13 and 14 are made narrower than half the diameter of the standard record and the upper edges of the strips are curved downwardly at the center as shown so that the title of the record printed on the center thereof may 30 be readily seen without removing the record from the pocket. The pockets are also arranged close enough together to permit the upper portion of one record to partly overlap the pocket next above, thus serving to 35 assist in holding the records flatly against the panel and also permitting a maximum number of records to be displayed on the panel.

By connecting the strips 13 and 14 together 40 through slots 12^a in the panel board a very strong pocket is formed at each side of the panel, and the weight of the records is supported largely by the connecting portions 17 of the pockets which bear upon the 45 lower edges of slots 12^a, thus relieving the strain on stitches 15. It also will be observed that the pockets are open along their lower edges throughout the greater portion 50 of the width of the pockets, thus preventing the accumulation of dirt and grit in the pockets that would be liable to injure the records.

What I claim is:

1. A display fixture panel comprising a 55 holding frame, a panel board therein provided with a vertical series of superposed transversely extending slots, and two series of oppositely disposed strips of flexible material secured at their ends to the faces of 60 the panel board, the lower edges of each

oppositely disposed pair of said strips being connected together through one of the slots in the panel board.

2. A display fixture panel comprising a frame, a panel board therein provided with 65 a vertical series of apertures centrally thereof, and two series of oppositely disposed strips of flexible material extending transversely of the panel board and secured at their ends to said board, the upper edges 70 of said strips being curved downwardly toward the middle thereof and the lower edges of each oppositely disposed pair of strips being connected together substantially midway thereof through one of the apertures 75 in the panel board.

3. A display fixture panel comprising a frame, a panel board removably held in the frame and provided with a transverse slot, 80 a pair of oppositely disposed strips of flexible material extending transversely across opposite faces of the panel board and stitched thereto at their ends, and binding strips stitched to the upper and lower edges of said strips, the lower edges of said strips 85 being stitched together intermediate their ends for a portion of their length at a point coincident with the slot in the panel board.

4. A panel board having a series of superposed apertures therein, and a plurality of 90 pairs of oppositely disposed article-holding strips secured at their ends to said board and connected together through said apertures intermediate their ends.

5. A panel board having a transverse slot 95 therein, and a pair of article-holding strips extending transversely of the board at opposite sides thereof, the ends of said strips being secured to the board and said strips having a connection at their lower edges 100 through said slot in the board.

6. A panel board having a transverse slot therein, and a pair of strips of flexible material stitched at their ends to said board and having their lower edges stitched together at a point midway their length to form an intermediate connection extending 105 through said slot.

7. A panel board having a vertical series of apertures therein, and strips of flexible 110 material secured at their ends to each side of said board and having their upper and lower edges free from said board throughout their length, said strips being arranged in pairs having their lower edges connected 115 together intermediate their ends through said apertures.

In testimony whereof I hereunto affix my signature.

NICHOLAS JOSEPH MIANO.
